DESIGN FOR A TOILET BRUSH

Eric Leopold Hugo Cesby, London, England

Application July 20, 1940, Serial No. 93,812
In Great Britain February 20, 1940

Term of patent 14 years

To all whom it may concern:

Be it known that I, Eric Leopold Hugo Cosby, a subject of the King of Great Britain, residing at London, England, have invented a new, original, and ornamental Design for a Toilet Brush, of which the following is a specification, reference being had to the accompanying drawing, forming part thereof.

I claim:

The ornamental design for a toilet brush, as shown.

ERIC LEOPOLD HUGO COSBY.
